COMMUNICATION SYSTEM

William E. Harding, Indianapolis, Ind.

Application April 15, 1938, Serial No. 202,196

17 Claims. (Cl. 179—1)

My invention relates to communication systems, such as telephonic railway-dispatching systems, in which a plurality of transmitters are located at intervals along a telephone line, and to an automatic volume-control apparatus for use in such systems as well as in other situations.

More specifically, my invention relates to a telephonic system incorporating one or more line boosters. In such a system, the booster receives current from the line, amplifies it, and returns the amplified current to the line. If the booster is located at one of the regular stations along the line, it may have associated with it a microphone, or other transmitter, and a sound-reproducing device, such as a loud speaker or telephone receiver.

It is the object of my invention to produce for use in such systems a booster having advantages over prior boosters of which I am aware. More specifically, it is my object to produce a line-booster in which any possibility of feed-back of amplified current into the amplifier is minimized or practically eliminated and in which variations in line-impedance will not adversely affect operation.

Another object of my invention is to produce an automatic volume-control apparatus usable in such systems or in other situations to maintain a substantially constant output irrespective of variations in input. In a railway dispatching system, this automatic volume-control apparatus will supply current for the sound-reproducing device, such as a loud-speaker.

Still another object of my invention is to associate a microphone or other transmitter with the booster in such a way that it will not feed into the automatic volume-control apparatus any of the sound it receives.

In carrying out my invention, I provide in the booster a pair of balanced circuits having a common or bridge portion, the latter being coupled to the input of an amplifier of any desired gain. The line is coupled to the balanced circuits in such a way that current from the line is applied to but one of the balanced circuits, and therefore flows through the bridge. Output from the amplifier is divided equally between the two balanced circuits and is therefore without any effect on the common or bridge portion thereof; but the coupling between the line and the two balanced circuits is such that amplified current is returned to the line. Coupled to the two balanced circuits I provide a compensating circuit that acts to reduce the extent to which changes in line-impedance affect the balance of

the balanced circuits with respect to amplified current.

A portion of the output of the amplifier associated with the booster may be supplied to a loud-speaker or other sound-reproducing device, desirably through an automatic volume-control apparatus. When constructed in accordance with my invention, such an automatic volume-control apparatus includes a pair of amplifiers whose outputs are connected, in opposed push-pull relation, to the loud-speaker. The input current of one of such amplifiers is made to vary proportionately with the input of the automatic volume-control apparatus, while the input to the other amplifier is made to vary in accordance with the amount by which the input to the automatic volume-control apparatus exceeds some predetermined value. This result is accomplished by an arrangement of balanced circuits to be described in detail hereinafter.

If a microphone or other transmitter is to be associated with the booster, its output is divided equally between the two balanced circuits of the booster so that it is not responsible for any current in the booster-bridge. In this way current from the microphone is kept out of the amplifier input.

The accompanying drawings illustrate my invention: Fig. 1 is a diagrammatic view of a complete station showing the booster circuits; Fig. 2 is a diagrammatic view of the preferred form of automatic volume-control apparatus; and Figs. 3 and 4 are fragmental views of automatic volume-control apparatus illustrating two different modifications thereof.

A booster constructed in accordance with my invention embodies a pair of associated balanced circuits 10 and 10' having a common portion, or bridge 11. Connected in the bridge 11 is the primary 12 of a transformer whose secondary 13 is connected to the input of an amplifier 14 of any desired construction. The output circuit of the amplifier 14 includes the primary 15 of a transformer having a secondary 16. A portion of the transformer-secondary 16 is included in a circuit 17 which also includes the primaries 18 and 18' of two transformers whose secondaries 19 and 19' are connected similarly in the balanced circuits 10 and 10' respectively. The windings 18, 18', 19, and 19' may form the four equal windings of a common type of transformer employed in telephone circuits. The circuit 17 may include a switch 20 for the purpose of cutting out the booster when desired.

In addition to windings 19 and 19', the bal-

anced circuits 10 and 10' also include respectively transformer windings 25 and 25'. Associated with the transformer winding 25, as by forming parts of another of the conventional four-winding transformers previously referred to, are similar windings 26, 27, and 28. Corresponding windings 26', 27', and 28' are associated with the winding 25'.

The booster is coupled to the line 30 by a coupling transformer having one winding 31, connected across the line 30, and a winding 32 whose terminals are connected to opposite ends of the windings 27 and 27' respectively. The other two ends of the windings 27 and 27' are connected together through one winding of a transformer 33 whose other winding is connected in series with a variable impedance 34. Thus a closed circuit is provided including, in the order named, the winding 27, the winding 32 of the coupling transformer, the winding 27', and the transformer 33. The two windings 26 and 26' are interconnected in opposed relation in series to form a bridge extending across the circuit just described from a point between the windings 27 and 32 to a point between the winding 27' and the transformer 33.

The two windings 28 and 28' are connected in opposed relation in series in a compensating circuit 37 which includes a variable impedance 36. In the booster described, line current, applied through the transformer 31-32, is divided into two components which flow in opposite directions through the windings 28 and 27 and in the same direction through the windings 26' and 27'. Because of its division between and opposite flow through the windings 26 and 27, this current is noninductive with respect to the circuit 10, but does create a proportional induced current in the circuit 10' (which includes the bridge 11). Through the coupling transformer 12-13, current in the bridge 11 is supplied to the amplifier 14.

The amplified current in the circuit 17, which is coupled to the amplifier-output by the transformer 15-16, flows through the transformer windings 18 and 18' and generates equal voltages across the windings 18 and 18'. These voltages are equal; and if the line impedance reflected through transformer 31-32 is equal to the impedance 34 as reflected through the transformer 33, the voltage across the winding 27 will equal the voltage across the winding 27', and no current will flow through the bridge consisting of the windings 26 and 26'. As the result of this, the voltage drop across the windings 25 and 25' will be equal, as will also the voltages across the windings 28 and 28'. As the windings 28 and 28' are connected in opposed relation, no current will flow in the compensating circuit 37.

The compensating circuit 37 tends to equalize the respective effects on circuits 10 and 10' of currents in the windings 26, 26', 27, and 27'. Therefore, if as a result of a lack of balance between line impedance and the impedance 34 the current flowing in winding 27 is unequal to the current flowing in winding 27', there will be induced in the circuit 37 a current which will tend to compensate for the effect of inequalities in the current in the respective windings 27 and 27'.

If there were no impedance in the compensating circuit, compensation would be substantially complete (except for transformer losses) and the circuits 10 and 10' would always be substantially balanced to amplified current irrespective of discrepancies between line impedance and the im-

pedance 34. On the other hand, if compensation were complete, line current in windings 26' and 27' would induce in circuit 37 a current substantially balancing the circuits 10 and 10' to line current, thus keeping line current out of the bridge 11 and therefore out of the amplifier input. The presence of the impedance 36, however, lowers the degree of compensation effected by the circuit 37. The impedance 36 is ordinarily adjusted to the lowest value which will not objectionably interfere with the transfer of energy from the line to the input of the amplifier 14; and I find in practice that with the impedance 36 so adjusted no noticeable feedback of amplified current into the amplifier input will occur even under wide variations in line impedance.

The impedance 36 desirably includes a phase-correcting condenser to compensate for the inductance of the windings 28 and 28'.

The impedance 34 preferably approximates mean line impedance both in value and character, but the adjustment is not at all critical.

If a microphone or other transmitter 40 is to be associated with the line at the station, it is desirably coupled to the balanced circuits 10 and 10' through the medium of a coupling transformer 41 the secondary of which is divided equally between the circuits 10 and 10' so that any effect of microphone current is kept out of the bridge 11 and therefore out of the amplifier input.

It may be desirable to provide in the bridge including the windings 26 and 26' a condenser 43 of a capacity such as to present relatively high impedance to low-frequency signal currents. This prevents shunting of low-frequency currents, such as bell-ringing currents, and also suppresses low-frequency oscillation.

If reproduction from the line is desired at the station a portion of the amplified current from the transformer-secondary 16 is supplied to a sound-reproducing device such as a loud-speaker 45, desirably through an automatic volume-control apparatus 46. The apparatus which I prefer to use is illustrated in detail in Fig. 2 and comprises two three-element vacuum tubes 50 and 50' whose plate circuits are connected in opposed push-pull arrangement and coupled by a transformer 51 to the speaker 48. The grid circuit of the tube 50' is coupled, as through a coupling transformer 53, with an intermediate circuit 54 including the secondaries 55 and 56 of two transformers A and B. The primaries of the two transformers A and B are connected respectively in two balanced circuits 57 and 58 which have in common a bridge 59. The balanced circuits 57 and 58 include complementary portions of an impedance 60 to an intermediate point of which one end of the bridge 59 is connected. In addition, the balanced circuits 57 and 58 include respectively the transformer secondaries 61 and 62 whose primaries are connected in series to the input circuit 63, which in this instance includes the transformer-secondary 16.

The coupling between the intermediate circuit 54 and the balanced circuits 57 and 58 is such that changes in the current flowing in the intermediate circuit 54 will affect differently the effective impedances in the respective circuits 57 and 58. To secure this result, I prefer to make the transformers A and B of different ratios and to connect their secondaries 55 and 56 into the circuit 54 in such a way that their secondary voltages are opposed to each other. As indicated in the drawings, the transformer A is a step-up transformer while the transformer B has a one-
75

to-one ratio, and the two secondaries 55 and 56 are connected together so that the effective E. M. F. causing current-flow in the circuit 54 is the difference between the respective voltages across such transformer-secondaries.

The grid circuit of the vacuum tube 50 is coupled by a transformer 64 to the secondary of a second transformer 65 whose primary is connected in the bridge 59. As a result, since the two amplifiers are connected in opposed relation, their joint output will depend upon the difference in value between the currents flowing in the circuit 54 and in the bridge 59 respectively. Upon any change of the current flowing in the input circuit 63, the voltages across the transformer secondaries 61 and 62 (which voltages are responsible for current flow in the balanced circuits 57 and 58) will be changed in the same sense, as will also the current flowing in the intermediate circuit 54. If it be assumed that the change in current in the input circuit is an increase, an increase will also occur in the current flowing in the intermediate circuit 54, which includes the secondaries 55 and 56 of the transformers A and B. The increase in current flowing through the transformer-secondary 55 will produce an effective decrease in the impedance of the primary of the transformer A. However, since the intermediate-circuit current flows through the transformer-secondary 56 in a direction opposite to that in which it flows through the secondary 55 of the other transformer, the increase in such intermediate-circuit current increases the effective impedance of the primary of the transformer B. The decrease in effective impedance in the primary of the transformer A and the increase in effective impedance of the primary of the transformer B which thus accompany an increase in the current flowing in the circuit 54 result in an increased current-flow through the bridge 59. As the bridge 59 is coupled to the grid circuit of the vacuum tube 50, that tube, acting through its plate circuit and the transformer 51, compensates for the increase in current flowing in the plate circuit of the tube 50' which results from the increase in current flowing in the intermediate circuit 54.

Similarly, a decrease in the current flowing in the input circuit will be accompanied by decreases in the strengths of the respective currents in the intermediate circuit 54 and in the bridge 59.

In the device as so far described, the strength of current flowing in the intermediate circuit 54 may be expressed as "kI", where I is the strength of current in the input circuit 63 and k is a constant depending upon the characteristics of the electrical apparatus; and the strength of the current in the bridge 59 may be expressed as "k'(I-I₀)", where I has the same value as before, k' is another constant depending upon electrical characteristics of the apparatus, and I₀ is the value of the current in the input circuit 63 when no current is flowing through the bridge 59.

If m represents the gain provided by the amplifier including the tube 50 and m' represents the gain provided by the amplifier including the tube 50', the net output of the two amplifiers will be represented by the equation:

$$70 (1) \quad \text{Output} = m k I - m' k' (I - I_0)$$

By suitable adjustment of the amplifiers, the constant m' may be made equal to

$$m' \frac{k}{k'}$$

Substituting this value for m' in Equation 1, that equation becomes:

$$70 (2) \quad \text{Output} = m k I - m k (I - I_0)$$

or

$$70 (3) \quad \text{Output} = m k I_0$$

As the quantities m, k, and I₀ are all independent of I, it is apparent that fluctuations in strength of the input current I will not affect the net output of the two amplifiers if the respective gains which those two amplifiers provide is properly selected with regard for other electrical characteristics of the apparatus.

To effect satisfactory regulation of the constants k, k', and I₀ in the above equations two circuits in addition to those already described may be employed. One of these circuits, indicated at 70 in Fig. 2, includes a variable impedance 71 and similar windings 72 and 73, which windings are embodied respectively in the transformers A and B, and acts as a load control circuit. The other, indicated at 74, includes a variable impedance 75 and a winding 76, the latter embodied in the transformer B and operating, as regulated by adjustment of the impedance 75, to determine, for any adjustment of the impedance 71, the value of the current I₀ in circuit 63 at which no current flows through the bridge 59.

The transformers A and B may each be of the common type of four-winding telephone transformer previously mentioned. In transformer B, the four windings are independently connected in the circuits 54, 58, 70, and 74. In transformer B, however, two of the windings are independently connected in the circuits 57 and 70 while the other two are connected in series to form the secondary 55 in the circuit 54. The same common type of four-winding transformer may be employed to form what is indicated in the drawings as two two-winding transformers 61 and 62.

With the arrangement illustrated in Fig. 2, the connection between the bridge 59 and the resistance 60 will be adjusted to create a condition of balance between the circuits 57 and 58 when circuits 54 and 71 are opened. The impedances 71 and 75 and the amplifiers are then adjusted to give the desired results. The preferred method of adjustment comprises maintaining in the circuit 63 a current of mean value while adjusting the impedances 71 and 75 and the amplifiers to such a condition that each amplifier will be operating near the middle of the straight portion of its response curve when desired output to the speaker is obtained.

The modified arrangement illustrated in part in Fig. 3 is identical with that shown in Fig. 2 except that the transformer-windings 55 and 56 are connected in opposed relation in the circuit 70 instead of in the circuit 54 while the circuit 54 includes the transformer-windings 72 and 73. This arrangement employs the same basic principle as does that of Fig. 2, the only difference between the two arrangements being that in that of Fig. 3 it is current in the circuit 70 rather than current in the circuit 54 which is employed to control the state of balance or unbalance of the two circuits 57 and 58 and hence the strength of current in the bridge 59.

In the arrangement illustrated in Fig. 4, the transformer-winding 76 and the circuit 74 associated with it are eliminated and the transformer windings 55 and 56 are connected in parallel.

rather than in series, in the circuit 54. An adjustable impedance 88 may be connected in series with the winding 56 to perform the same function as is performed by the impedance 75 of Fig. 5. 2. In such an arrangement, the current flowing through winding 56 will not be the same as that flowing in winding 55, but it will vary in the same sense as the current in winding 55 varies and thus will co-operate with the current in winding 10 55 to control the degree of unbalance of the circuits 57 and 58.

If, for any reason, there should be any difference in phase-relationship between currents in the secondaries of the transformers 53 and 64 15 it may be corrected for by appropriate use of one or more condensers (not shown) in the circuit 54 and bridge 58.

Many modifications and arrangements of my invention other than those specifically illustrated 20 and described are possible. Further, the invention is adapted to many uses other than that in connection with which it has been described. The booster may be used with or without the associated microphone and loud speaker, or with 25 either alone. If the loudspeaker is used, the automatic volume-control apparatus may or may not be employed, as desired. The automatic volume-control apparatus may be used apart from the booster, as in a public-address system to 30 maintain a substantially constant sound-output irrespective of the loudness of the speaker's voice.

I claim as my invention:

1. A booster for telephone lines or the like; comprising a pair of balanced circuits including 35 a bridge portion common to both; an amplifier having an input circuit coupled to said bridge portion and an output circuit coupled independently to said two balanced circuits; two four-winding transformers having their primaries 40 connected respectively in said balanced circuits; an intermediate line-circuit including, in order, a secondary winding of one of said transformers, an impedance, and a secondary winding of the other transformer; the line being coupled to said 45 intermediate circuit at a point therein between the said two transformer windings; a connection including another secondary winding of each transformer and extending across said intermediate circuit from a point between one of the 50 windings therein and said impedance to a point between the other winding therein and the coupling with the line; and a compensating circuit including an impedance and the remaining windings of said transformers connected in series 55 and in opposed relation.

2. A booster as set forth in claim 1 with the addition that the impedance in said intermediate circuit is approximately equal to mean line impedance.

3. A booster for telephone lines or the like; comprising a pair of balanced circuits including a bridge portion common to both; an amplifier having an input circuit coupled to said bridge portion and an output circuit coupled independently to said two balanced circuits; an intermediate circuit coupled to the line and to each of 65 said balanced circuits to create in said bridge portion a current proportional to incoming line currents; and a compensating circuit including windings connected oppositely in series; said windings being coupled respectively to said balanced circuits and also to said intermediate line-circuit.

4. A booster for telephone lines or the like;

comprising a pair of balanced circuits including a bridge portion common to both; an amplifier having an input circuit coupled to said bridge portion and an output circuit coupled independently of said two balanced circuits; a pair of 5 windings coupled to each of said balanced circuits; an intermediate circuit including, in order, one winding of one pair of windings, an impedance, and one winding of the other pair of windings; the line being coupled to said intermediate 10 circuit at a point between said two windings; the remaining two windings being connected in opposed series relation across said intermediate circuit dividing it into two arms, one containing a winding and said impedance and 15 the other containing the other winding and said line-coupling; and a compensating circuit tending imperfectly to compensate in said balanced circuits for inequalities in the respective effective impedances in the two arms of said intermediate 20 circuit.

5. The invention set forth in claim 4 with the addition that said impedance is approximately equal to line impedance.

6. A booster for telephone lines or the like; comprising a pair of balanced circuits including a bridge portion common to both; an amplifier having an input circuit coupled to said bridge portion and an output circuit coupled independently to said two balanced circuits; an intermediate line-circuit divided into two arms by a cross-connection; one arm of said intermediate circuit being coupled to the line and the other arm containing an impedance approximately 25 equal to line impedance; each arm of said intermediate line-circuit being coupled to said balanced circuits by couplings of different effectiveness; said cross-connection being oppositely coupled to said balanced circuits.

7. A booster for telephone lines or the like; comprising a pair of balanced circuits including a bridge portion common to both; an amplifier having an input circuit coupled to said bridge portion and an output circuit coupled independently to said two balanced circuits; an intermediate line-circuit divided into two arms by a cross-connection; one arm of said intermediate circuit being coupled to the line and the other arm containing an impedance approximately 35 equal to line impedance; each arm of said intermediate line-circuit being coupled to said balanced circuits by couplings of different effectiveness.

8. The invention set forth in claim 7 with the addition of a microphone similarly coupled to said 40 two balanced circuits.

9. In a line booster, a pair of balanced circuits having a common bridge portion, an amplifier having its input coupled to said bridge portion and its output divided equally between said balanced circuits, a divided line circuit having two arms coupled respectively to said balanced circuits, and a compensating circuit coupled to each arm of said line circuit and to each of said balanced circuits and including an impedance.

10. In a line booster, a pair of balanced circuits having a common bridge portion, an amplifier having its input coupled to said bridge portion and its output divided equally between said balanced circuits, a divided line circuit having 70 two arms coupled respectively to said balanced circuits, and a compensating circuit coupled to each arm of said line circuit and to each of said balanced circuits.

11. In a line booster, a pair of balanced circuits 75

having a common bridge portion, an amplifier having its input coupled to said bridge portion and its output divided equally between said balanced circuits, a divided line circuit having two arms coupled respectively to said balanced circuits, and means tending imperfectly to equalize as between said balanced circuits the effect of unequal impedances in the arms of said line circuit.

5 12. In a line booster, a pair of balanced circuits having a common bridge portion, an amplifier having its input coupled to said bridge portion and its output divided equally between said balanced circuits, a divided line circuit having two arms, one of said line-circuit arms being coupled directly to one of said balanced circuits and indirectly to the second balanced circuit, the other of said line-circuit arms being coupled directly to the second balanced circuit and indirectly to the first balanced circuit.

10 13. In combination, a speaker, a pair of vacuum tubes having grid-circuits and plate circuits with the latter coupled in opposed push-pull arrangement to said speaker, an intermediate circuit coupled to the grid-circuit of one of said tubes, a pair 15 of balanced circuits having a common bridge portion coupled to the grid-circuit of the other of said tubes, a pair of transformers of different ratios, each of said balanced circuits including the primary of one of said transformers, the secondaries of said transformers being connected in series in opposed relation in said intermediate circuit, an input circuit, and a second pair of 20 transformers having their primaries connected in said input circuit and their secondaries respectively connected in said balanced circuits.

25 14. In combination, a speaker, a pair of vacuum tubes having grid-circuits and plate circuits with the latter coupled in opposed push-pull arrangement to said speaker, an intermediate circuit coupled to the grid-circuit of one of said tubes, a 30 pair of balanced circuits having a common bridge

portion coupled to the grid-circuit of the other of said tubes, a pair of transformers having their secondaries connected respectively in said balanced circuits, an input circuit including the primaries of said transformers, and dissimilar coupling means coupling said intermediate circuit with said balanced circuits respectively.

5 15. In combination, a speaker, a pair of vacuum tubes having grid-circuits and plate circuits with the latter coupled in opposed push-pull arrangement to said speaker, an intermediate circuit coupled to the grid-circuit of one of said tubes, a pair of balanced circuits having a common bridge portion coupled to the grid-circuit of the other of said tubes, dissimilar coupling means 15 coupling said intermediate circuit with said balanced circuits respectively, an input circuit, and means for creating across corresponding portions of said balanced circuits a potential difference proportional to the current in said input circuit. 20

16. In combination, a speaker, a pair of vacuum tubes having grid-circuits and plate circuits with the latter coupled in opposed push-pull arrangement to said speaker, an input circuit, means for varying the current in one of said grid circuits 25 in proportion to variations in the current in said input circuit, and means for varying the current in the other grid circuit in proportion to the extent by which the current in the input circuit exceeds a predetermined value. 30

17. In combination, an input circuit, an output circuit, a pair of amplifiers connected in opposed push-pull relation and feeding said output circuit, means for supplying one of said amplifiers with current proportional to current in said input circuit, and means for supplying the other amplifier with current proportional to the amount by which current in said input circuit exceeds a predetermined value. 35

WILLIAM E. HARDING. 40
